United States Patent

Des. 240,137
Patented June 1, 1976

240,137

TELEPRINTER

Paul A. Jenkins, Groton, and Richard C. Schneider, Marlboro, Mass., assignor to Digital Equipment Corporation, Maynard, Mass.

Filed Sept. 16, 1974, Ser. No. 506,138

Term of patent 14 years

Int. Cl. D14—02

U.S. Cl. D26—5 C

FIG. 2

FIG. 1

FIG. 4

FIG. 3

FIG. 1 is a perspective view of a teleprinter showing our new design;

FIG. 2 is a front elevational view thereof;

FIG. 3 is a left side elevational view thereof; and

FIG. 4 is a top plan view thereof.

The rear of the teleprinter is substantially plain and unornamented.

We claim:

The ornamental design for a teleprinter, substantially as shown and described.
